UNITED STATES PATENT OFFICE.

JOHN WAKEHAM AND JOHN CUNNINGHAM, OF TORONTO, ONTARIO, CANADA.

GRATE.

SPECIFICATION forming part of Letters Patent No. 396,248, dated January 15, 1889.

Application filed April 5, 1888. Serial No. 269,744. (No model.)

To all whom it may concern:

Be it known that we, JOHN WAKEHAM and JOHN CUNNINGHAM, both mechanics, and both residents of the city of Toronto, in the county 5 of York, in the Province of Ontario, Canada, have jointly invented certain new and useful Improvements in Grates, of which the following is a specification.

The object of the invention is to design a 10 serviceable grate which may be easily shaken, and from which the clinkers may be readily removed; and it consists, essentially, of a grate having an open center and designed to be shaken in a longitudinal or horizontal direction, the center opening in the grate having 15 an independent grate inserted in it and designed to be revolved, substantially as herein-after more particularly explained.

Figure 1 is a perspective view of our grate 20 in its normal position. Fig. 2 is a similar view showing the center grate partially revolved. Fig. 3 is a view showing the grate tilted.

For the purpose of illustrating our invention we have chosen a rectangular stove-grate; but it will of course be understood that circular grates may also be constructed on the same principle, and that our grate will be equally as serviceable in furnaces.

30 A is a frame having a series of projecting fingers, B, formed around it, as shown, and constituting a narrow grate extending around in proximity to the walls of the fire-pot.

C are trunnions formed on the grate A at 35 either end and fitting into notches made in the frame of the stove or furnace.

D are a series of fingers formed around the spindle E, either in triangular shape, as indicated, or in any other angular form. The 40 spindle E is suitably journaled in the frame of the furnace or stove in such a position that

the flat surfaces of the fingers D in their normal position, as shown in Fig. 1, are substantially level with the fingers B. Room is left at the ends of the grate A to permit it to be 45 shaken longitudinally, and the spindle E is so supported that it may be readily revolved for the purpose of causing the fingers D to act on the clinkers which may accumulate at the bottom of the fire.

50 The angular shape of the fingers causes them to grind up and remove the clinkers when the spindle is revolved, as specified.

As the top surface of the fingers D are substantially level with the fingers B, the fire will 55 not collect below any of the fingers, which are thus surrounded on three sides by open air-spaces, which prevent the fingers from burning.

It will be noticed that the trunnions C are 60 set off the center of the grate A, so that when dumped the natural inclination of the grate will be to resume its horizontal position, and, owing to the location of the fingers D, it is impossible to dump the grate A farther than into 65 a substantially vertical position.

What we claim as our invention is—

The combination, with the frame, of the 70 grate A, journaled therein on trunnions C, set to one side of the center and formed with fingers B, projecting inside and outside of the same and with a central opening, and the spindle E, formed with angular fingers D, working in the central opening of the grate A, and all arranged and operating substantially as 75 shown and described.

Toronto, March 17, 1888.

JOHN WAKEHAM.

JOHN CUNNINGHAM.

In presence of—

CHARLES C. BALDWIN,
CHARLES H. RICHES.
